(57) **CLAIM**

The ornamental design for a flat paint brush wiper for positioning on a plastic paint bucket, as shown and described.

DESCRIPTION

FIG. 1 is a front elevational view of a flat paint brush wiper for positioning on a plastic paint bucket showing my new design; FIG. 2 is a rear elevational view thereof; FIG. 3 is a top plan view thereof; FIG. 4 is a bottom plan view thereof; FIG. 5 is a left side elevational view thereof; FIG. 6 is a right side elevational view thereof; and, FIG. 7 is a perspective view thereof showing the paint bucket in broken lines. The broken lines are for illustrative purposes only and form no part of the claimed design.
